UNITED STATES PATENT OFFICE

KARL PSCHORR, OF ARZBERG, GERMANY, ASSIGNOR TO SCHUMANN CHINA CORPORATION, OF NEW YORK, N. Y.

DESIGN FOR A PLATE OR SIMILAR ARTICLE

Application filed April 21, 1930. Serial No. 35,338. Term of patent 3½ years.

To all whom it may concern:

Be it known that I, KARL PSCHORR, a citizen of the Republic of Germany, residing at Arzberg, Bavaria, Germany, have invented a new, original, and ornamental Design for a Plate or Similar Article, of which the following is a specification, reference being had to the accompanying drawings, forming part thereof.

Figure 1 is a plan view of a portion of the border of the plate shown in Fig. 2, the ornamentation shown being continued throughout the border.

I claim:

The ornamental design for a plate or similar article as shown and described.

KARL PSCHORR.
